UNITED STATES PATENT OFFICE.

JESSE J. HOOKS, OF DONNA, TEXAS.

THERMOSTATIC FIRE-EXTINGUISHING DEVICE.

1,143,762.

Specification of Letters Patent. Patented June 22, 1915.

Application filed September 15, 1914. Serial No. 861,880.

To all whom it may concern:

Be it known that I, JESSE J. Hooks, a citizen of the United States, residing at Donna, in the county of Hidalgo and State of Texas, 5 have invented new and useful Improvements in Thermostatic Fire-Extinguishing Devices, of which the following is a specification.

This invention relates to a thermostatic 10 fire extinguishing device, the object of the invention being to provide a device of this character which is simple of construction, reliable and efficient in operation and adapted to be automatically thrown into operation 15 to supply an extinguishing fluid when a fire breaks out and the temperature at the protected point reaches a predetermined degree; and further to provide means for sounding an alarm when the device is set 20 into action, and which will close or cut off the flow of fluid when the fire is extinguished.

The invention consists of the features of construction, combination and arrangement 25 of parts herein fully described and claimed, reference being had to the accompanying drawing in which:—

Figure 1 is a sectional elevation of a fire extinguishing device embodying my invention, showing the parts in normal position. Fig. 2 is a similar view showing the arrangement of the parts when the device is in operation. Fig. 3 is a sectional plan view on line 3—3 of Fig. 1. Fig. 4 is a section on line 4—4 of Fig. 1.

Referring to the drawing, 1 designates a supply pipe for an extinguishing fluid, which communicates with one side of a conductor 2 terminating in a discharge device or spray 40 nozzle 3, the flow of fluid through the nozzle being controlled by a discharge valve 4 normally held closed against a seat 5.

The conductor 2 communicates at its upper end with a pressure chamber or cylinder 45 6 in which is arranged a diaphragm, piston or other movable pressure controlled element. In the present instance a diaphragm is shown consisting of upper, lower and intermediate spring metal corrugated disks 50 7, 8 and 9, the upper and intermediate disks being peripherally connected with each other, and the intermediate and lower disks being centrally apertured and connected centrally by a coupling ring or flange 10, while the lower disk is peripherally fastened in a tight manner to the casing, as indi-

cated at 11. The upper and lower disks of the diaphragm are thus movably connected, but, as the upper disk is free from connection with the casing and joined by the intermediate disk to the resilient intermediate disk which is centrally connected with the lower disk, which is fixed to the casing, it is evident that the upper disk is permitted to have a greater amplitude or movement 65 than the lower disk. The diaphragm separates the casing 6 into upper and lower chambers 12 and 13, and the lower disk 8 is subjected to pressure within the chamber 13, while the upper disk 7 is subjected to the 70 opposing pressures within both chambers, whereby the diaphragm is ordinarily maintained in a universal or valve closing position, as hereinafter described.

The valve 4 is connected by a stem 14 with 75 the diaphragm disk 7, which extends upward through the ring 10 and is fixed to the center of the disk 7, and a coiled spring 15 is suitably arranged, such as between the bottom of the casing 6 and the valve 4, as 80 shown, to serve by its expansive action to compensate for the difference in the amplitude of motion of the disks 7 and 8 to maintain the parts in a normally balanced position against the pressures of the chambers 85 12 and 11 to hold the diaphragm in natural position and the valve 4 seated to cut off communication between the pipe 1 and sprayer 3 until the diaphragm is properly operated for a valve opening action. 90

The chamber 6 is in communication at its bottom with the pipe 16, and hence water normally flows from the pipe 1 to the chamber 13 and exerts its pressure against the diaphragm disk 8, and in order to normally 95 place the diaphragm disk 7 under a substantially equal opposing pressure a by-pass pipe or duct 16 is provided between the chamber 13 and chamber 12 by way of a port 17 communicating with a guide and 100 flow passage 18 arranged within a conductor tube 19 communicating with and extending upwardly from the top of the casing 6, by which, when the port 17 is open, the water from the chamber 13 will pass to the chamber 12 so that the pressures in said chambers will be normally equal, the pressure in the chamber 12, however, being supplemented by the pressure of the spring 15, whereby 105 the balancing pressures upon the diaphragm 110 disks are balanced in accordance with their respective degrees or amplitudes of motion,

to balance the working pressures in an effective manner. It will be understood, however, that when the flow of fluid through the by-pass to the chamber 12 is cut off, a 5 preponderance of pressure will be established in the chamber 13, resulting in an upward movement of the diaphragm within the casing 6 and the opening of the valve 4 for the discharge of the extinguishing fluid 10 from the pipe 1 through the sprayer or nozzle 3.

The tube 19 has a guiding and supporting extension 20 of reduced diameter and provided with a valve seat 21 and a vent or relief outlet 22. A valve 23 is arranged to close upwardly against the seat 21, against which it is held by a spring 24, to normally confine the fluid within the chamber 12 and prevent its escape. This valve has a 15 pending portion or guide member 25 which is movable in the guide way 18 and is adapted to control the port 17 to cut off the flow of fluid therethrough under certain conditions. When the valve 23 is moved downwardly to open the outlet 22 and close the port 17, the flow of fluid pressure into the chamber 12 will be cut off, and on the ensuing upward movement of the diaphragm, wherein the discharge valve 4 is opened, a 20 proportion of the fluid contained in the chamber 12 is allowed to vent through the opening 22 to prevent resistance to the upward movement of the diaphragm.

A thermostatic device is provided for controlling the double valve 23-25, and comprises a bracket 26 formed with a tubular portion 27 at its base embracing the part 20 and secured thereto by a set screw 28. The bracket is in the form of an open oblong 35 rectangular frame and has arranged therein a thermostat 29 composed of a pair of superposed corrugated metallic disks peripherally connected to form a chamber in which is enclosed a volatile liquid and expansive agent 40 which, when exposed to heat, will volatilize or expand and force the two disks apart.

The upper disk has centrally fixed thereto a threaded rod 30 which adjustably engages a threaded bore 31 in the upper arm of the 45 bracket and is adapted to be secured in position by a lock nut 32. A vertically movable stem 33 has its upper end disposed below the center of the thermostat and its lower end secured to the valve 23, said stem 50 passing through a restricted guide bore 34' at the upper end of the extension 20 of the valve casing 19, the construction being such that upon the expansion of the thermostat the stem 33 will be engaged and forced 55 downward, thus moving the valve 23 away from its seat 21 while at the same time depressing the valve member 25 to close the port 17, it being understood, of course, that the thermostat may be constructed to expand 60 to a working degree at any desired 65

temperature. A spring 34 surrounds the upper portion of the stem between the upper end of the extension 20 and guard or shield 35 fixed to said stem and co-operates with the spring 24 to hold the valve 23 seated and the 70 depressible stem in normal position until the thermostat is positively expanded to the required degree to actuate the valves, said springs serving also after operation of the parts and contraction of the thermostat to 75 return said parts to normal position. The guard or shield 35 is in the form of a concavo-convex disk arranged to intersect and shield the thermostat from any small amount of water which may jet through the bore 34' during the exhaust of water from the chamber 12, thus preventing cooling and contraction of the thermostat during the time the device should be positively and reliably in action for the discharge of the extinguishing fluid through the sprayer nozzle 3. Any suitable kind of alarm circuit may be employed in connection with the apparatus for the purpose of sounding an alarm when a fire breaks out and the apparatus is 80 set into operation. In the present instance a circuit is shown comprising conductors 36 and 37, a battery or other suitable source of electric supply 38 and a bell or other alarm device 39, said conductors being connected 85 respectively with the thermostat and the stem 33 or some other suitable part of the valve or the connections for operating the valve 23 from the thermostat, which are suitably insulated from each other and 90 adapted upon the expansion of the thermostat to be coupled to energize the alarm circuit and sound the alarm.

It will, of course, be understood that the apparatus may be supported and arranged in any suitable manner at the point to be protected, and that the valves 4 and 23 are normally maintained in closed position and the valve 25 in open position, while the thermostat is set for expansion at a predetermined temperature to open the relief valve 23 for the purpose of setting the apparatus into operation when a fire breaks out at or near the protected point and the temperature rises to such degree. Upon the expansion of the thermostat when a fire breaks out, the stem 33 is depressed, the valve 23 opened and the valve 25 closed, whereupon an increase of pressure in the chamber 13 ensues by which the diaphragm in the casing 6 is elevated and the fluid displaced in the chamber 12 and allowed to vent through the outlet 22. The valve 4 will thus be opened for the discharge of the extinguishing fluid from the pipe 1 through the sprayer 3. At the same time the expansion of the diaphragm will close the electric circuit and sound the alarm. When the fire is extinguished and the temperature again falls, the thermostat contracts and the valve 100 105 110 115 120 125 130

actuating stem 33 is returned to normal position by the action of the springs 24 and 34, thus restoring the parts to normal position, closing the valve 23 against the seat 21 and opening the valve 25 to uncover the port 17, whereupon there will be a resumption of the flow of fluid pressure through the pipe 16 to the chamber 12, thus reestablishing a substantial equalization of pressures in the chambers 12 and 13, whereupon the spring 15, coupled with the retractive action of the diaphragm disk 7, will again close the valve 4 against its seat 5 and cut off the discharge of the extinguishing fluid.

15. The apparatus is thus adapted to operate in a positive, reliable and efficient manner and to be controlled at a predetermined temperature, insuring a positive extinguishment of the flames in the case of the breaking out 20 of a fire at the protected point, and the subsequent restoration of the parts to a normal condition, thus preventing the building or apartment from being flooded. If, however, the fire should only be partly extinguished and should again break out, the 25 apparatus, upon a subsequent increase of temperature to the determined degree, will again be thrown into operation to extinguish the flames.

30. While the construction disclosed is preferred, it will of course be understood that any modifications in the arrangement of parts, and the use of equivalents may be employed, within the spirit and scope of the 35 invention as defined in the appended claims.

I claim:

1. In a fire extinguishing apparatus, the combination of a casing, a diaphragm in said casing consisting of connected disks 40 having different amplitudes of movement, the disk of the lesser amplitude of movement being connected with the casing, a fluid supply pipe, means connecting the casing with said supply pipe for the supply of fluid 45 pressure on opposite sides of said diaphragm, a discharge valve connected with the diaphragm disk of greater amplitude of movement, and means for creating variations of pressure in the casing on opposite sides of the diaphragm under determined 50 conditions to effect an opening movement of said valve.

2. A fire extinguishing apparatus, the combination of a casing, a diaphragm in said 55 casing consisting of outer disks and a central disk, one of said outer disks being fixed to the casing so as to have a lesser amplitude of movement than the other outer disk, a fluid supply pipe provided with an outlet, means establishing communication between said pipe and the casing on opposite sides of said diaphragm, a discharge valve controlling said outlet and connected with the diaphragm disk of greatest amplitude of 60 movement, and means for establishing varia-

tions of pressure on opposite sides of the diaphragm under certain conditions to effect an opening movement of said valve.

3. In a fire extinguishing apparatus, the combination of a casing, a diaphragm in 70 said casing, comprising outer disks connected by an intermediate disk, one of said outer disks being fixed to the casing so as to have a lesser amplitude of movement than the outer disk, a fluid supply pipe, means connecting the same with the casing for the supply of fluid pressure on opposite sides of the diaphragm, a discharge valve connected with the diaphragm disk having the greatest amplitude of movement, means for establishing variations of pressure in the casing on opposite sides of said diaphragm to effect an opening movement of said valve, and spring means for resisting the opening movement of the valve and coöperating 80 with the diaphragm to normally hold the valve in closed position.

4. In a fire extinguishing apparatus, the combination of a fluid supply pipe having a discharge outlet, a casing in communication 90 at one side with said pipe, a diaphragm in said casing, a relief passage communicating with the opposite side of the casing, a by-pass leading from the first-named side of the casing and communicating with the opposite side thereof through said relief passage, a discharge valve controlling said outlet, and connected with the diaphragm, a double valve controlling the relief passage and by-pass, and thermostatically controlled 95 means for adjusting said double valve to simultaneously open the relief passage and close the by-pass.

5. In a fire extinguishing apparatus, the combination of a fluid supply pipe having a discharge outlet, a casing in communication 105 at one side with said pipe, a relief passage at the other side of the casing, a by-pass establishing communication between the pipe and the second named side of the casing through said relief passage, a diaphragm within the casing, a valve controlling said discharge passage and actuated by the diaphragm, a double valve controlling said relief passage and by-pass, a spring for normally maintaining said valve in position to close the relief passage and open the by-pass, and a thermostat acting on said valve under 110 certain conditions to open the relief passage and close the by-pass.

6. In a fire extinguishing apparatus, a fluid supply pipe having a discharge passage, a casing in communication at one side with said pipe, a relief passage communicating with the other side of the casing, a by-pass connecting the pipe with the other side of the casing through said relief passage, a diaphragm within the casing, a discharge valve controlling said outlet and controlled 125 by the diaphragm, a double valve within the 130

relief passage normally arranged to close said passage and maintain the by-pass open and movable to open said passage and close said by-pass, spring means for holding said double valve in the first named position, a stem connected with said double valve, a thermostat adapted to act upon said stem to move the valve to the second named position, and a guard or shield carried by said

stem, substantially as and for the purposes 10 described.

In testimony whereof I affix my signature in presence of two witnesses.

JESSE J. HOOKS.
